DESIGN.

G. L. CROWELL, Jr.
BACK FOR BRUSHES, &c.

No. 19,803.

Patented May 6, 1890.

UNITED STATES PATENT OFFICE.

GILBERT L. CROWELL, JR., OF ARLINGTON, NEW JERSEY, ASSIGNOR TO
DOMINICK & HAFF, OF NEW YORK, N. Y.

DESIGN FOR BACK FOR BRUSHES, &c.

SPECIFICATION forming part of Design No. 19,803, dated May 6, 1890.

Application filed January 30, 1890. Serial No. 338,666. Term of patent 7 years.

To all whom it may concern:

Be it known that I, GILBERT L. CROWELL, Jr., of Arlington, in the county of Hudson and State of New Jersey, have invented and produced a new, original, and useful Design for Backs for Brushes, Mirrors, and other Toilet Articles, of which the following is a description, reference being made to the accompanying photograph, which fully illustrates the design.

The body of the design consists of various groupings of flowers interspersed with vines and leaves, as follows:

At or near the middle of the design is a group of chrysanthemums or similar comparatively large flowers *c*, with their petals overlapping and thrown up in high relief, and at or near each end of the design is a group of buttercups or similar small flowers *d*, having their petals also bunched together in bold relief. Occupying the spaces between and around these groups of flowers are vines *e*, irregularly-arranged leaves *f*, and, less prominent, buds or other small flowers *g* in medium

relief. The sunken spaces, as at *i i*, between the different figures of the design are stippled or roughened.

The design may be arranged within an ornamental border consisting of a wavy and laterally-scalloped band *a*, which is slightly raised or in low relief, and which runs along the sides of the back of the brush or other article near the edges thereof and terminates in the volute scrolls *b* at the rounded ends of the back.

The leading features of my design consist of the prominent groups of flowers with open petals wrought in high or bold relief, with the intermediately-arranged vines and leaves in lower relief.

What I claim is—

The design for backs of brushes, mirrors, and other toilet articles, substantially as herein shown and described.

GILBERT L. CROWELL, JR.
